EDWIN E. GREAVES, OF SYRACUSE, NEW YORK, ASSIGNOR TO CROUSE-HINDS COMPANY, OF SYRACUSE, NEW YORK, A CORPORATION OF NEW YORK.

SCREW-RETAINING DEVICE.

1,105,647.

Specification of Letters Patent.

Patented Aug. 4, 1914.

Application filed March 10, 1914. Serial No. 823,685.

To all whom it may concern:

Be it known that I, EDWIN E. GREAVES, a citizen of the United States, and a resident of Syracuse, in the county of Onondaga and 5 State of New York, have invented a certain new and useful Screw-Retaining Device, of which the following is a specification.

This invention has for its object a screw retaining device particularly applicable for 10 preventing the screws, which secure the covers to electrical conduit outlet boxes, from removal from the covers; and it consists in the novel features of construction herein-after set forth and claimed.

15 In describing this invention, reference is had to the accompanying drawings, in which like characters designate corresponding parts in all the views.

Figure 1 is a sectional view, partly in 20 elevation, of one form of conduit outlet box, the screws of which are provided with my invention. Fig. 2 is an inverted plan view of the cover. Fig. 3 is a plan view of the screw retaining device. Fig. 4 is a cross- 25 sectional view thereof. Figs. 5, 6 and 7 are enlarged fragmentary sectional views through the cover, Fig. 5 illustrating the screw retaining device when placed on the screw, Fig. 6 showing said device when 30 moved into operative position, and Fig. 7 illustrating the action of the device when an attempt is made to pull the screw out of the hole. Fig. 8 is a view, partly in section, 35 showing the dies and punches and the operations used in forming this screw retaining device.

This screw retaining device comprises a washer which is here shown in the form of a disk, the washer having a marginal portion and a hollow, axially-projected, truncated, conoidal boss and a perforation at the top of the boss of less diameter than the screw with which the device is designed to be used, the edge of the boss around the 45 perforation being compressed so that it is of greater density and hardness than the remaining part of the boss and is rigid compared with the remaining part of the boss, which part is comparatively flexible so that 50 the boss can flatten toward the plane of the body of the washer. The compressed or condensed edge around the perforation of the boss is so thin that a portion thereof will take into the threads of the screw.

55 1 designates a conduit outlet box, and 2

the cover therefor, which is retained in position by screws 3 usually passing through unthreaded openings 4 in the cover and threading into lugs 5 in the box. The openings 4 are of larger diameter than the screws 60 3 and extend through the cover, and preferably corresponding ends of the openings 4 communicate with recesses or countersinks inclosed by ribs projecting from one face of the cover concentric to said openings and 65 spaced apart therefrom. The heads of the screws engage the opposite face of the cover about the other ends of the openings 4.

6 designates the screw retaining device in the form of a disk of less diameter than the 70 ribs inclosing the recesses or countersinks communicating with corresponding ends of the openings 4, said device having an axially-projected, truncated, conoidal boss 7 which has a perforation at the top thereof 75 of less diameter than the threaded part of the screw 3.

The walls of the boss 7 taper toward the perforation, as seen in Fig. 4, forming a thin edge around the perforation so that 80 said edge 8 or a portion thereof will take into the threads of the screw, as seen in Figs. 6 and 7. The thinning of the edge 8 around the perforation is formed by compressing said edge, which edge before being compressed is of the same thickness as the major part of the boss and washer, as seen in Fig. 8. As here shown, the upper side of the boss is formed slightly convex, and the lower side is conical, the convex surface 85 curving at 9 into a plane approximately parallel to the body of the washer as the curved surface nears the edge 8. The curving of the upper face of the boss arranges 90 the thin edge 8 in position to engage the threads most effectively, and the arrangement of the conical inner surface braces said edge and tends to prevent the tearing away 95 of the same.

This screw retaining device is formed by dies, as seen in Fig. 8, and the blank 10 is placed in the female lower die 11 and the upper die 12 which also carries a punch 13, first punches perforation in the blank 10 and then the male die 12 coöperating with the lower die 11 forms the boss 7 and compresses the margin thereof around the perforation with the edge 8.

In operation, this screw retaining device 110 is first placed on the end of the screw as

indicated in Fig. 5 and forced along the screw into the position shown in Fig. 6, in which it is located at the bottom of a countersink at the inner end of the unthreaded screw hole 4. As the perforation is of smaller diameter than the screw, the thin margin 8 around the perforation has a sort of ratcheting action over the thread due to the slight flexibility of the major part of the 5 boss, and when the screw is pulled outwardly a portion or portions of the hard thin edge around the perforation take into the threads if a force is applied to the screw 10 tending to flatten the cone toward a plane, 15 as seen in Fig. 7.

What I claim is:

1. A device for retaining a screw in an opening larger in diameter than the shank of the screw, said opening extending entirely 20 through a body, and the head of the screw engaging with one face of the body about one end of the opening, said device 25 engaging with the portion of the screw shank projecting beyond the opposite face of the body and coacting with said face last named, and comprising a disk having a marginal portion and a central portion offset from the marginal portion in the direction of the end of the screw shank, and provided with a central opening tapering inwardly from the face of the disk opposite to that from which the central portion is offset, the portion of said tapering opening of smaller diameter being of less diameter 30 than the screw thread on the shank, and said device being flexible and slidable lengthwise of the shank from the end thereof toward the head of the screw, substantially as and for the purpose described.
- 40 2. A device for retaining a screw in an opening larger in diameter than the shank of the screw, said opening extending through a body, and the head of the screw co-operating with one face of the body, said device 45 engaging with the portion of the screw shank projecting beyond the opposite face of the body, and comprising a disk having a marginal portion and an offset portion having a tapering wall, said disk having a 50 central opening through the same, a portion of the wall of the part of said opening passing through the offset portion of the disk being of less thickness than the major portion of the disk and of less diameter than 55 the screw shank, said offset portion yielding for permitting the disk to be forced lengthwise of the shank from the end thereof toward the head of the screw and closing in to grip the threads of the shank when the 60 disk contacts with the adjacent face of the body and the screw is moved toward the front face thereof, causing a relative movement toward the disk of the end of the shank opposite the head of the screw, substantially 65 as and for the purpose specified.

3. A combined cover and securing means therefor, comprising a plate having an opening extending entirely through the same transversely thereof, a screw having a threaded shank passing loosely through said 70 opening and a head for co-operating with one face of the plate for preventing relative movement of the screw in one direction, and a disk of a diameter greater than said opening slidable lengthwise of the shank of the 75 screw in one direction and frictionally engaging the same, said disk being carried by the part of the shank projecting beyond the face of the plate opposite to that with which the head of the screw coacts, and co-operating with said face for limiting the movement of the screw in a second direction, substantially as and for the purpose set forth.

4. A combined cover and securing means therefor, comprising a plate having an 80 opening extending through the same transversely thereof, and a rib extending from one face of the plate concentric to said opening and spaced apart therefrom, providing a recess about one end of the opening, 85 a screw having a head co-operating with the opposite face of the plate, and a threaded shank of less diameter than said opening projecting through the same and beyond the first-named face of the plate, and a flat disk 90 frictionally secured to said projecting portion of the shank and slidable lengthwise thereof in one direction, said disk being adapted to occupy said recess and co-operate with the bottom thereof for preventing 95 accidental detachment of the screw from the plate by a relative movement of the screw in one direction, substantially as and for the purpose described.

5. A screw retaining device comprising a 105 washer having a hollow projected, truncated, substantially conoidal boss, and a perforation at the top of the boss for receiving the screw, the major part of the boss being comparatively flexible and capable of flattening 110 toward the plane of the washer, the wall of the boss being tapered toward the perforation and the margin thereof around the perforation condensed so that it is rigid compared with the major part of the boss, the 115 condensed edge being designed to take into the threads of the screw, substantially as and for the purpose specified.

6. A screw retaining device comprising a 120 washer having a hollow, projected, truncated, conoidal boss and a perforation at the top of the boss, the perforation being of less diameter than the screw the device is designed to be used with, and the edge of the 125 boss around the perforation being compressed thinner than the normal thickness of the wall of the boss forming a thin edge to take into the threads of the screw, substantially as and for the purpose set forth.

7. A screw retaining device comprising a 130

washer having a hollow, projecting truncated, substantially conoidal boss, and a perforation at the top of the boss of less diameter than the screw the device is designed to
5 be used with, the margin of the boss around the perforation being condensed forming a thin margin, rigid compared with the remaining portion of the boss, and the outer face of the boss being convex and curving
10 into a plane approximately parallel to the body of the washer as said surface nears the perforation, the inner face being conical,

substantially as and for the purpose described.

In testimony whereof, I have hereunto 15 signed my name in the presence of two attesting witnesses, at Syracuse, in the county of Onondaga, and State of New York, this 2nd day of March, 1914.

EDWIN E. GREAVES.
